UNITED STATES PATENT OFFICE.

WALTER HENTSCHEL, OF CHEMNITZ, GERMANY, ASSIGNOR TO SÄCHSISCHE MASCHINENFABRIK VORM. RICH. HARTMANN, AKTIENGESELLSCHAFT, OF CHEMNITZ, GERMANY.

SPINNING DEVICE.

Application filed December 9, 1920. Serial No. 429,578.

To all whom it may concern:

Be it known that I, WALTER HENTSCHEL, a citizen of the German Republic, residing at Chemnitz, Germany, have invented certain new and useful Improvements in Spinning Devices, of which the following is a specification.

The continuous spinning machine (ring frame) has not as yet been adopted in the manufacture of carded yarns because the supervision of these machines was hitherto rendered very difficult by the known forms of small spinning tubes. It is true that tubes of this kind are known which no longer necessitate the threads being drawn through with the aid of hooks or special iron wire. In the case of these tubes the threads are pushed through automatically, as for example by an oblique bore, or a bore whose size increases towards the point.

The tube according to the present invention is distinguished from the aforementioned type by a simple, straight, cylindrical bore that is easier to produce. The operation of automatically drawing the thread through the tube is caused to be performed by so shaping the opening above the point of the tube through which the thread issues that the rapid rotation of the tube gives rise to a sucking effect in the direction from the entrance to the exit of the thread, this sucking effect being strong enough to draw the thread through the tube, so that the manipulations to be performed during the operation of the machine are of the simplest kind.

A constructional form of the novel tube is shown in the drawing in which

Fig. 1 is a side view showing the relative positions of the tube and the delivery rollers,

Fig. 2 shows the tube of Fig. 1 turned through an angle of 90° and

Fig. 3 is a cross section on the line 3—3 of Fig. 2.

Fig. 4 shows the position of the rotated tube between the feed and delivery rolls of a spinning frame and

Fig. 5 illustrates the shape of the blunt end of the tube.

The roving enters at the blunt end *o* of the tube and issues at its pointed end *s*. The tube is furnished slightly above its point with a notch *a* that extends approximately to the middle line through the tube, see Figs. 1 and 2. The lateral surfaces *r*¹ and *r*² (Fig. 3) of the cavity *a* are made wedge-shaped so that they act in the manner of a ventilator when the tube is rotated quickly and produce the suctional effect required for drawing the thread through the tube.

In order to make the draft obtained between the feed and delivery rolls *z* and *z*₁, Fig. 4, as uniform as possible, the known expedient is employed of causing the roving to execute an oscillating or flinging motion, as in spinning with self-spinning devices. This motion is brought about by providing the end of the tube where the thread enters with small notches *n*, Fig. 5, that are confined to the inner wall of the tube, and which, when the tube is rotated, carry the thread round for a part of a revolution and then release it, thus producing the desired oscillatory motion of the thread.

I claim:

1. A spinning tube for yarn spinning machines having a longitudinal thread receiving opening and provided with means at one terminal of the opening responsive to rotation of the tube to produce an air current directed from the entering point toward the exit point of the thread whereby to automatically draw the thread through the tube.

2. A spinning tube for yarn spinning machines having a pointed end and a longitudinal opening extending from end to end, the pointed extremity of the tube being cut away to provide faces arranged to produce an air current through the tube during rotation of the latter whereby to automatically draw the thread through said tube.

In testimony whereof I affix my signature.

WALTER HENTSCHEL.
